UNITED STATES PATENT OFFICE

WALTER E. TRENT, OF NEW YORK, N. Y., ASSIGNOR TO THE TRENT PROCESS CORPORATION, A CORPORATION OF DELAWARE

PROCESS AND APPARATUS FOR TREATING CARBONACEOUS MATERIAL

Application filed November 4, 1927. Serial No. 230,954.

This invention relates to a method of, and apparatus for, heat treating various carbonaceous materials such as coals, oil shales, lignites, petroleum oils and the like. The invention is particularly applicable to the treatment of various solid or semi-solid carbonaceous materials for the purpose of distilling off the vaporizable constituents and recovering the residue in the form of carbonized fuel.

In the distillation and carbonization of carbonaceous materials of the classes specified, it is highly desirable to cause the whole body of material undergoing treatment to be subjected to as uniform a temperature as possible, thereby causing the distillation and carbonization to proceed at substantially the same rate throughout the mass and preventing overheating or useless heating of localized portions thereof, while other portions are being brought to the desired treated condition.

The present invention has for a principal object a process for transmitting heat to the material undergoing carbonization by means of heated conductive members having portions positioned either in the path of the material being treated in its passage through the heating apparatus, or in such proximity thereto that heat will be transmitted from such members substantially uniformly to all parts of the carbonaceous material being treated, the conductive members also having other portions extending outside the carbonizing zone in heat receiving relation to a heat source, such as a burner, grate or the like.

Another object of the invention is to provide means for carrying out the process either as a continuous operation or intermittently in an economical and expeditious manner.

A further object of the invention is to provide means for maintaining a close heat control in treating carbonaceous material, so that, if desired, the distillation of the volatiles in the material being treated may be carried on at a temperature close to but slightly

50 below the normal coking temperature for the

material being treated, thereby permitting the carbonaceous residue to be recovered in finely powdered form.

Still another object of the invention is to provide means for producing gas from carbonaceous material of the classes specified in a simple and convenient manner.

Other objects and advantages of the invention will appear as the description proceeds.

Referring now to the drawings, in which like numerals refer to like parts, and in which

Figure 1 is a vertical part sectional and part elevational view of one form of apparatus capable of being used to carry out the process;

Figure 2 is a vertical sectional view through one of the heating units shown in Figure 1 and taken on the line 2-2 of said figure;

Figure 3 is a vertical sectional view through one of the carbonizing retorts shown in Figure 1 and taken on the line 3-3 of said figure;

Figure 4 is a view in perspective illustrating more or less diagrammatically a horizontal section through a single heating unit and an adjoining retort both similar to those shown in Figs. 1 and 3;

Figure 5 is a vertical sectional view of a modified form of apparatus;

Figure 6 represents more or less diagrammatically the direction of flow of the hot gases and the direction of flow of the material being treated over the heat conductive members in apparatus such as that shown in Figure 5;

Figure 7 illustrates in cross section a number of forms of the heat conductive members which may be used in practicing the invention.

In the drawings, 10 indicates generally one form of carbonizing apparatus embodying the present invention. This apparatus is shown as comprising three heating or combustion-chambers 12 and two intermediate treating members or retorts 14, the several chambers being separated by the walls 16. It will be understood that a greater or smaller number of the heating chambers and treating re-

- retorts may be assembled without departing from the invention; also, that one heating chamber may be associated with two retorts in the same manner as illustrated or two heating chambers may be associated with one retort. Extending from one of the side walls 18 of the apparatus 10 to the other, and embedded therein and in the intermediate walls 16, are heat conductive members 20. Preferably these members consist of metallic rods or bars, for example, of cast iron, although any heat resistant material possessing similar heat conductive properties and the requisite strength may be used.
- In the apparatus illustrated in Figs. 1, 2 and 3 the heat conductive members or rods 20 are shown as arranged in vertically spaced rows so as to provide a plurality of superimposed tunnel-like passages from end to end of each of the retort chambers 14. The rows of rods 20 also serve as supports and guideways for the trays 26 containing the carbonaceous material which is to be treated. The openings 22 are provided in the end walls 24 in alignment with the passages above mentioned, thus permitting introduction and withdrawal of the trays. The trays 26 are preferably made of a highly conductive material such as cast iron so as to facilitate the transmission of heat from the rods to the carbonaceous material being treated. In order to permit the evolved vapors to pass more freely upward through the retorts to the outlets to the vapor line 28 leading to a suitable vapor recovery apparatus not shown, the trays may be provided with foraminous or reticulated bottom portions as indicated at 30 in Fig. 4.
- The heating chambers 12 as shown in Fig. 2 are provided with a plurality of upstanding and depending baffle walls 32 so disposed as to cause the products of combustion to pass from the grate 34 or other suitable heat source in a circuitous path back and forth over the rods 20 as indicated by the arrows, and finally discharge to the stack 36. Where a plurality of heating chambers are provided the products of combustion may be led from those heating chambers not immediately connected to the stack to offtake flues 38 and a connecting flue 40.
- It may be desirable to introduce air, steam or other gases into the retort chambers, for example, when the apparatus is being used in producing gas. I have, therefore, provided the openings 42 which may be controlled by the slide valves 44. The apparatus may be operated as follows:
- Trays 26, filled with the carbonaceous material which is to be subjected to a carbonization heat treatment and which may, for example, be a powdered coal-hydrocarbon oil amalgam such as is disclosed in my U. S. Patent No. 1,420,164, are inserted through the openings 22 in the end walls 24 and moved

along in any suitable manner on the rods 20 until the retort is completely filled with trays of the material. The openings 22 are then closed and the carbonaceous material is subjected to heat transmitted from the heating chambers by the conductive rods 20 until the distillation and carbonization have been carried to the desired extent. The length of time required for the carbonizing treatment will vary somewhat depending upon material being treated. In treating amalgamated masses of powdered anthracite coal of the type found in Rhode Island, a heating period of from one to two hours will suffice.

The course taken by the vapors distilled from the carbonaceous material is indicated by the arrows shown as applied to the retorts and the vapor line in Figs. 1 and 4. Similarly, the course taken by the products of combustion in their passage to the stack is indicated by the arrows applied to the heating chambers and flue passages in Figs. 1, 2 and 4.

Instead of conducting the heat treatment as a batch or periodic operation, it may be desirable to introduce trays of fresh material intermittently, the introduction of each fresh tray being accompanied by the withdrawal from the opposite end of a given row of trays in the retort of a tray containing material which has been subjected to the desired amount of treatment.

It may also be desirable to introduce the trays of fresh material at the end of the retort farthest removed from the grate or grates 34 and cause them to be moved intermittently toward the zone of highest heat adjacent the grate or grates 34. Again, it may be desired to cause the trays to travel intermittently through the retort on one level and then to return them on a succeeding level and so on, back and forth until a single tray has traversed all of the levels. In this way the charging and withdrawal of the trays will proceed with greater regularity than where fresh trays are introduced to all of the levels of the retort at one charging operation. It will be appreciated that the construction shown permits of considerable flexibility of operation with respect to the charging and discharging of the metal being treated as well as with respect to the course the material may take in its passage through the retort and the duration of the treatment.

As will be readily understood from an inspection of the drawings and the above description, the hot products of combustion in passing over the portions and the rods 20 disposed in the heating chambers give up their sensible heat to the rods. This heat is conducted to those portions of the rods disposed within the retorts from which portions it is transmitted to the material to be treated. Heat transfer from the rods to the carbonaceous material will take place largely by conduction through the metal of the trays, al-

though considerable transfer by means of radiant heat, particularly in those portions of the retorts opposite the hotter portions of the heating chambers, will take place. Also, in 5 case the trays are provided with foraminous or reticulated bottoms permitting the vapors from lower trays to pass upward through the carbonaceous material in the upper trays, considerable heat transfer from the rods 20 to 10 the material undergoing treatment will take place by convection currents. Owing to the fact that the trays are relatively shallow and the rods are so spaced vertically as to provide but a small clearance between the tops of 15 the trays and the next row of rods, the heated rods are brought into close proximity not only to the material in the trays being supported by them, but also to the upper surface of the material in the trays being supported 20 by the next lower row of rods, thus facilitating the transmission of heat uniformly to all portions of the material undergoing treatment.

In Fig. 5 a modified construction is shown 25 in which in lieu of trays 26 for carrying the carbonaceous material through the retort, means is provided for causing the material to move by gravity through the retort in heat transmitting relation with heated rods similar to those illustrated in Figs. 1 and 4 inclusive. In this figure is shown a vertically arranged retort 14' having arranged at each side and parallel therewith heating chambers 12'. Extending laterally of said heating 30 chambers and said retort are metal rods 20 arranged in horizontal rows. The rows of rods 20 are spaced relatively closely together as compared with the rows shown in Figs. 1, 2 and 3. Also, the rods in the respective rows 35 are so spaced horizontally that rods of adjacent rows are not in vertical alignment, thus causing the carbonaceous material in its passage through the retort to follow zig-zag paths between the rods of the successive rows, 40 as indicated diagrammatically by the arrows in the portion marked *b* of Fig. 6. Likewise, the products of combustion from the grates 34 are caused to pass upward in a zig-zag path over those portions of the rods in the 45 heating chambers as indicated diagrammatically by the arrows in the portion marked *a* of Fig. 6, and thus are caused to be brought into intimate contact therewith.

In operation, the carbonaceous material to 50 be treated is introduced through the charging hopper 46 and caused to be more or less evenly distributed in the retort 14' by means of the cone-shaped member 48 positioned in the mouth of the conduit 50 leading from the 55 hopper 46, and by means of the invested frusto-conical ring 52 which is disposed beneath the member 48, both of which members are supported from the walls of the retort 14' by means of the radially extending members 60 54. The passage of the material through the

conduit 50 is shown as controlled by means of a slide valve 56. In order to discharge the carbonized material from the retort, an endless conveyor 58 is provided at the bottom of the retort. Vaporized constituents of the material undergoing heat treatment are led off to suitable recovery apparatus not shown by means of a vapor line 28'. The course of the evolved vapors and the products of combustion is indicated in Fig. 5 by means of the single arrows applied respectively to the retort and the heating chambers. The course of the carbonaceous material and the solid residue is indicated by means of double arrows. 70

According to the modification illustrated in Fig. 5, the process may be conducted either continuously or intermittently, and owing to the arrangement of the rods 20, the carbonaceous material in its passage downward through the retort will be repeatedly brought 75 into intimate contact with the heated rods, thus effecting a high and uniform rate of heat transmission.

The rods or bars 20 may take different cross sectional forms as indicated by the modifications designated by the letters *e*, *f*, *g* and *h* in Fig. 7.

It will be understood that the process may be carried out in other forms of apparatus than that shown. Such a construction is 90 shown, for example, in my prior co-pending application Ser. No. 612,080, filed January 11, 1923, and to the extent of the matter so shown in said prior application, but not claimed therein, the present application is 95 a continuation.

Another form of the apparatus embodying features of the present invention, and which is adapted particularly for the treatment of finely divided carbonaceous material so as to volatilize the vaporizable constituents and recover the residue in the form of finely divided carbonized particles is 100 shown in my co-pending application Ser. No. 135,471, filed September 14, 1926, of which 105 the present application is a continuation in part as to those features relating to the transmission of heat by means of conductive members.

Various modifications may be made as to 110 the details of construction of the apparatus and of the procedure outlined without departing from the scope of the invention which is not to be deemed to be limited other than as indicated in the appended claims. 115

What I claim is:

1. An apparatus for treating carbonaceous materials, comprising a retort, a combustion chamber disposed adjacent said retort, a plurality of metal rods having portions disposed within said combustion chamber and other portions disposed within said retort, said rods being disposed in vertically spaced, horizontally aligned rows, containers for said material adapted to be supported by, and 120
2. An apparatus for treating carbonaceous materials, comprising a retort, a combustion chamber disposed adjacent said retort, a plurality of metal rods having portions disposed within said combustion chamber and other portions disposed within said retort, said rods being disposed in vertically spaced, horizontally aligned rows, containers for said material adapted to be supported by, and 125
3. An apparatus for treating carbonaceous materials, comprising a retort, a combustion chamber disposed adjacent said retort, a plurality of metal rods having portions disposed within said combustion chamber and other portions disposed within said retort, said rods being disposed in vertically spaced, horizontally aligned rows, containers for said material adapted to be supported by, and 130

5 moved along, said rows, heat producing means in said combustion chamber, and means for causing the products of combustion to be brought into intimate relation with those portions of said rods in said combustion chamber.

10 2. A carbonizing process which comprises positioning a plurality of vertically spaced rows of heat conductive members with portions of said members within a carbonizing zone and other portions thereof outside said zone, supporting carbonizable material to be treated upon the portion of each of said rows positioned within said zone, applying a carbonizing heat to the portions of said members positioned outside said zone, causing said material to be carbonized by heat conducted from the portions of said members outside said zone to the portions thereof within said zone, and passing vapors evolved from the material supported on the lower of said vertically spaced rows through the material supported upon the upper rows.

15 3. A carbonizing apparatus comprising a retort, a plurality of heat conducting members having portions thereof disposed within said retort and other portions extending outside said retort, means for supporting material to be carbonized upon the portions of 20 said members disposed within the retort, and means for applying a carbonizing heat to the portions of said members extending outside said retort, said means for supporting material comprising a container adapted to be moved along said members.

25 4. A carbonizing apparatus comprising a retort, a plurality of heat conducting members having portions thereof disposed within said retort and other portions extending outside said retort, said members being disposed in vertically spaced horizontally aligned rows, containers adapted to be supported by and moved along said rows, and means for applying a carbonizing heat to the portions 30 of said members extending outside said retort.

40 In testimony whereof, I have signed my name to this specification this 2nd day of November, 1927.

45 50 WALTER E. TRENT.
